UNITED STATES PATENT OFFICE.

HENRY H. WARNER, OF TACOMA, WASHINGTON.

CAR-BRAKE.

SPECIFICATION forming part of Letters Patent No. 781,578, dated January 31, 1905.

Application filed June 9, 1903. Serial No. 160,726.

To all whom it may concern:

Be it known that I, HENRY H. WARNER, a citizen of the United States, residing at Tacoma, in the county of Pierce and State of Washington, have invented certain new and useful Improvements in Car-Brakes; and I do hereby declare the following to be a full, clear, and exact description of the invention, such as will enable others skilled in the art to which it applies to make and use the same.

The object of this invention is to provide an improved form of let-down brake-staff that can be operably supported and operated in either the vertical or the horizontal position.

A further object is to provide in such a device means for supporting the uncoupling-lever and also means whereby the several parts constitute washer-plates for the truss-rod of the car.

With these objects in view, and others, my invention comprehends the construction, arrangement, and combination of parts, as hereinafter set forth with reference to the drawings and then pointed out in the claims.

Referring to the drawings illustrating an apparatus embodying my invention, Figure 1 is a front elevation. Fig. 2 is a plan view. Fig. 3 is a side elevation. Fig. 4 shows the supporting member in plan. Fig. 5 shows the supporting member in front elevation. Fig. 6 shows the bracket for retaining the brake-staff in a horizontal position. Fig. 7 shows the brake-staff swivel. Fig. 8 shows the gravity-latch.

In the several views, in which the characters of reference indicate corresponding parts, to a supporting member or plate A on the buffer-beam of the car is secured a bracket B, having a journal portion B', in which is pivoted a swivel-socket C. The brake-staff D has its lower end portion rotatably carried in the socket C. This bracket has an arm B², containing a slot B³, arranged in vertical alinement with the socket C. When the brake-staff is in its vertical position, it lies in this slot. A gravity-latch E is pivoted on the arm B² and is normally retained by its heavier portion e in the position shown in Fig. 2, so as to close the slot B³ and securely hold the brake-staff in the vertical position; but by swinging the arm e upward the arm e² is

swung away from the slot and the brake-staff may be moved out of the slot B³. The brake-staff may be swung to the horizontal position, in which it is supported by a bracket F, having a supporting-arm f. The arm f forms, 55 with the bracket, a circular bearing f', having an open upper side for receiving the brake-staff, and leading to this bearing is an outwardly-inclined slot f², one wall f³ of which overhangs the open side of the bearing. Since 60 the bearing f' is in horizontal alinement with swivel-socket C when the brake-staff is in its horizontal position, it follows that in order to lower the brake-staff into the bearing the staff must be sprung slightly outward to permit its 65 passing wall f³, and when supported in the bearing this wall will prevent jars from lifting the staff out of position. When in this position, the wheel d on the brake-staff lies at the side of the car and will permit freight on 70 the car to extend beyond the end and onto an adjacent car having a similar let-down brake-staff. The brake-staff has a ratchet-wheel H, that when in the horizontal position engages a pawl K, pivoted on the bracket F. When 75 the brake-staff is in the vertical position, the ratchet-wheel H engages a pawl K², pivoted on the bracket B. By mounting pawls K and K² on the journal members immediately adjacent bearings f' and B³ the ratchet-wheel on 80 the brake-staff is reliably engaged by one or other of these pawls when the staff is in operative position. The bracket B also has a socket portion B', that serves as a washer-plate for the truss-rod M, as shown in Fig. 1. 85 The bracket F has a socket F', that rotatably supports the uncoupling lever or arm N.

Without limiting myself to the details of construction and arrangement shown and described, what I claim as new, and desire to 90 secure by Letters Patent, is—

1. The combination of a supporting member, a brake-staff rotatably mounted therein and arranged to be held in either a vertical or horizontal operative position, and a bracket 95 for supporting the staff in a horizontal position, said bracket being adapted to support an uncoupling-lever.

2. The combination of a supporting member, a brake-staff rotatably mounted therein 100

and arranged to be held in either a vertical or horizontal operative position, a bracket for supporting the staff in a horizontal position, and an uncoupling - lever mounted in said bracket.

3. The combination of a supporting member, a brake-staff pivoted thereon to occupy either a vertical or a horizontal position, a ratchet - wheel on the brake - staff, a slotted bearing for supporting the staff in an upright position, a pawl pivoted adjacent the bearing, a bearing having an open upper side for receiving the staff when in a horizontal position, a pawl pivoted adjacent this bearing and positioned to engage with the ratchet-wheel when the staff is in its horizontal position, and means for locking the staff in the slotted bearing in engagement with the first-named pawl.
- 10 4. The combination of a supporting member, a socket pivoted to the member, a brake-staff carried by the socket and arranged to be supported in both the vertical and horizontal positions, a bracket arranged to support the 15 brake-staff, when in the vertical position, a second bracket arranged to engage the brake-staff when in the horizontal position, and a gravity-latch arranged to lock the brake-staff in the first bracket, substantially as described.
- 20 5. The combination of a supporting member, a socket pivoted to the member, a brake-staff carried by the socket and arranged to be

supported in both the vertical and horizontal positions, a bracket arranged to engage the brake-staff when in the horizontal position, a 35 pawl carried by the latter bracket, a ratchet-wheel on the brake-staff arranged to engage the said pawl, and a pawl on the supporting member arranged to engage the said ratchet-wheel when the brake-staff is in the vertical 40 position, substantially as described.

6. The combination with a supporting member, a brake-staff, and a bearing carried by the supporting member and arranged to permit the rotation of the brake-staff therein in 45 either a vertical or horizontal operative position; of a slotted bearing in vertical alinement with the first bearing when the brake-staff is in a vertical position and arranged to receive the staff when in such position, a third bearing 50 in horizontal alinement with the first bearing when the brake-staff is in a horizontal position, said third bearing having an open upper side and arranged to support the staff when in such horizontal position, and an inclined 55 slot leading to said third bearing and having one wall overhanging the open side thereof.

In testimony whereof I affix my signature in the presence of the subscribing witnesses.

HENRY H. WARNER.
